RECEPTACLE AND LIGHTER

Filed March 14, 1929

INVENTOR
Andrew Leitheuser,
BY
Mr. H. Campbell,
ATTORNEY

UNITED STATES PATENT OFFICE

ANDREW LEITHEUSER, OF EAST ORANGE, NEW JERSEY

RECEPTACLE AND LIGHTER

Application filed March 14, 1929. Serial No. 346,886.

This invention relates to an improved receptacle and lighter, the receptacle being adapted for holding cigarettes, cigars or tobacco.

5 The object of the invention is to combine these two articles not only for assembly but to enable the lighter to be lighted when the lid of the receptacle is being closed. Furthermore, the lighter has a cover or lid which 10 can not be latched in closed position unless the main lid is closed. This assures closing of the two lids and also prevents the lighting of the lighter while it is in the pocket.

The invention relates to certain details 15 of construction which will be more fully described hereinafter and finally embodied in the clauses of the claim.

The invention is illustrated in the accompanying drawings in which Figure 1 is a 20 perspective view of one form of my combined case and lighter. Figure 2 is a section through the lighter part, partly broken away. Figure 3 is a section on line 3—3 in Figure 2. Figure 4 is a perspective view of 25 the combined push rod and latch used in the lighter.

In the article that I have invented, the receptacle, which I shall call the case, and the lighter are combined in a way to provide 30 for coordinating the parts so that when the lid of the case is released and flies open by spring pressure it releases the lid of the lighter which also is opened by a spring and then when a cigarette or the like is removed 35 from the case and the lid of the case is snapped shut it actuates the spark mechanism to ignite the wick of the lighter. This action also places the latch that holds the lid of the lighter closed in position to engage 40 the lid of the lighter and when this latter lid is closed the whole device is again entirely closed.

In the drawings I have shown a cigarette case as comprising the receptacle, the case 45 being shown at 10 and the lid being shown at 11, these parts being hinged together at 12 and a spring 13 opens the lid when it is released. Any usual form of holding means such as a catch 14 and the lip 15 is used to 50 hold the lid shut and the lip can be released

by pressing on the finger piece 16. The lighter is illustrated in general by the reference numeral 17 and comprises the usual fuel space 18 with a wick 19 that has its end 20 exposed for ignition. The ignition is by 55 means of the usual flint which I show at 21 which is pressed by a spring 23 in the holder 22 against the rough sparking wheel 24 which is readily rotatable on a shaft 25. The sparking wheel is rotated in one direction by 60 the pinion 26 which has a slight side motion on a shaft 25 so that the ratchet 27 is not operative when the pinion 26 rotates in the reverse direction.

A spring 28 abuts on the pinion 26 and on 65 the arm 29 to yieldingly hold the pinion against the sparking wheel. The pinion is rotated by a sliding rack 30 which has teeth 31 that mesh with the teeth of the pinion 26. This rack or bar 30 has a head 32 and is normally held retreated by a spring 33 which bears against the front wall 34 of the lighter and on the end of a sleeve 35 which is fastened to the head 32. The spring 33 and the sleeve 35 surround the pin 36 which keeps 70 them aligned. The head 32 is on the outside of the back wall 37 of the lighter and is engaged by the part 38 of the lid 11 which is beyond the partition 39 of the lid which 75 partition acts as the end of the compartment that holds the cigarettes or the like. The lighter has a lid 40 which is normally pushed open by a spring 41 and is hinged at 42 so as to be swung to uncover the lighter to enable 80 the flame of the end 20 of the wick to be utilized.

The lid has a catch 40^a which is disposed so that it will engage the latch 42 which is at the end of the bar 30 but this engagement 85 can not take place unless the bar 30 is pushed forward which is normally done by the part 38 of the lid 11 but in case of failure to ignite it can be operated by hand as will be seen from Figure 1.

In using the device it will be assumed in 90 this description that the lid 11 is shut and the supplemental lid 40 is shut. When the cigarette is to be extracted and lighted the finger piece 16 is pushed and the lid 11 flies open under the influence of the spring 13. 95 100

This releases the head 32 on the bar 30 and the spring 33 acts to force the bar 30 back and this releases the catch 41 and the lid 40 flies open under the influence of the spring 40a. All this takes place instantaneously. A cigarette is then extracted and the lid 11 is snapped shut between the thumb and fingers of the hand. This pushes the bar 30 forward, the rack 31 rotates the pinion 36 which 10 operates the spark wheel and the wick is ignited. The lid 11 is held in its closed position by the catch 14 and the lip 15 and the lid thus holds the bar 30 in its forward position. As the cigarette is lighted the lid 40 15 is closed and it will stay shut because latch 42 is advanced to the position where it receives the catch 40a. The front wall of the lighter has a recess or hole 43 into or through which the latch 42 can project. The lid can 20 be provided with a snuffer or extinguisher 44 which passes down over the wick and the small opening through which it projects.

The cap 45 indicates a closure for the usual 25 filler opening through which fuel can be supplied to the reservoir of the lighter.

Various changes can be made in the form and relative positions of the parts of this device without departing from the scope of the invention as defined in the claims.

30 I claim:—

1. A receptacle and a lighter secured together, a hinged lid to cover both, an ignition device in the lighter and including a push rod having a head on one end and a 35 catch engaging part on the other end, the head being disposed so as to be pushed when the lid is closed whereby the lighter is actuated and the catch engaging end of the rod presented to locking position, and a supplemental lid on the lighter with a catch to engage the said catch-engaging end of the rod.

2. A combined receptacle and lighter having a lid for closing the receptacle and for engaging the lighter when closed, a lid on the 45 lighter and a catch for the latter lid moved into locking position by the lid of the receptacle.

3. A combined lighter and receptacle, a hinged lid on the receptacle, a sparking device in the lighter including a push rod slideable therein, one end of the rod being exposed 50 for engagement by the lid, the other end having a means for retaining a second lid, and a said second lid arranged on the lighter 55 with a catch for engaging the retaining end of the rod.

4. A receptacle and a lighter combined in one structure, a lid hinged on the receptacle, a spring to force the lid open when released, a 60 lid on the lighter, the latter lid having a spring to force the lid open when released, and a latch for engaging the second lid to retain it in closed position, and a spring for pushing the latch to non-engaging position, 65 the latch being located so as to be held in

engaging position by the closed lid of the receptacle.

5. A receptacle and lighter combined in one article, a spring lid on the receptacle, a spring lid on the lighter, a spring latch for the second lid and located so that it is held in locking position by the lid on the receptacle, whereby the opening of receptacle lid releases the lid on the lighter, a sparking device in the lighter and a connection from the sparking device to the latch whereby on closing the lid of the receptacle the said lid actuates the sparking device.

In testimony whereof I affix my signature.

ANDREW LEITHEUSER.
